(57) **CLAIM**

The ornamental design for a lighted vehicle gear-shift knob, as shown and described.

DESCRIPTION

FIG. 1 is a perspective view of a lighted vehicle gear-shift knob showing may new design. The gear shift lever is shown in broken lines for illustrative purposes only and forms no part of the claimed design;

FIG. 2 is a front elevational view thereof, the rear side, left side and right side being a mirror image thereof;

FIG. 3 is a top plan view thereof; and,

FIG. 4 is a rear elevational view thereof.
